UNITED STATES PATENT OFFICE

ROBERT A. NORTHCOTT, OF LOS ANGELES, CALIFORNIA

DESIGN FOR A SHAMPOO LAVATORY

Application filed November 12, 1932. Serial No. 45,946. Term of patent 14 years.

To all whom it may concern:

Be it known that I, ROBERT A. NORTHCOTT, a citizen of the United States, and residing at Los Angeles, in the county of Los Angeles and State of California, have invented a new, original, and ornamental Design for a Shampoo Lavatory, of which the following is a specification, reference being had to the accompanying drawing, forming part thereof, in which—

Figures 1 and 2 are respectively views in front and in side elevation of a shampoo lavatory showing my new design.

I claim:

The ornamental design for a shampoo lavatory as shown.

ROBERT A. NORTHCOTT.
